TIE RACK

Lawrence M. Lefkof, 2509 Gladiolus Lane,
Dallas, Tex. 75233

Filed Feb. 18, 1975, Ser. No. 550,775

Term of patent 14 years

Int. Cl. D6—01

U.S. Cl. D6—117

FIG. 1

FIG. 2

FIG. 4

FIG. 3

FIG. 5

FIG. 6

FIG. 7

FIG. 8

FIG. 1 is a perspective view of a tie rack showing my new design;

FIG. 2 is a side elevational view of FIG. 1;

FIG. 3 is a front elevational view of FIG. 1;

FIG. 4 is a top plan view of FIG. 1;

FIG. 5 is a perspective view of a second embodiment of the design of FIG. 1;

FIG. 6 is a side elevational view of FIG. 5;

FIG. 7 is a front elevational view of FIG. 5; and

FIG. 8 is a top plan view of FIG. 5.

I claim:

The ornamental design for a tie rack, substantially as shown and described.
